UNITED STATES PATENT OFFICE.

JACOB THOMSEN JACOBSEN, OF METROPOLITAN, CALIFORNIA.

POLE-TIP.

No. 852,561.

Specification of Letters Patent.

Patented May 7, 1907.

Application filed December 3, 1906. Serial No. 346,163.

To all whom it may concern:

Be it known that I, JACOB THOMSEN JACOBSEN, a citizen of the United States, residing at Metropolitan, in the county of Humboldt, State of California, have invented a new and useful Improvement in Pole-Tips for Carriage and Wagon Poles, of which the following is a specification.

This invention relates to a device or appliance to be affixed and used on the outer end of carriage and wagon poles for the purpose of preventing certain classes of accidents while driving and is accomplished by two projecting shoulders which prevent the neck-yoke from accidentally slipping off the end of the pole. I attain these objects by the mechanism illustrated in the accompanying drawing, in which,—

Figure 1 is a view in perspective of the appliance when in place and ready for use; Fig. 2 is a horizontal section of the end of the carriage pole, showing the entire mechanism of the appliance; Figs. 3 and 4 represent the two pieces which, while in place, show the projecting shoulders.

Similar letters refer to similar parts throughout the several views.

The blades C C, with spiral spring between them, are inserted in slot J in the pole end, and secured by the rivet D. When the eye of the yoke is pulled on over the end of the pole A, the shoulders, or projecting points of

the blades C C are depressed, but spring back to position when the yoke has been drawn up against the collar B. To release the yoke, 35 C C are depressed by the thumb and finger.

F is a stiff spiral spring which keeps the projecting points or shoulders in place.

E E and H are stops to prevent C C from turning around in slot J.

G G are eyelets through which rivet D is fastened.

K K are rests to hold spring F in place.

The object of the invention is to prevent accidents on grades or other places by the 45 accidental breaking or unfastening of the tugs or swing tree, whereby the pole end is allowed to drop to the ground, thus rendering the carriage unmanageable.

What I claim as my invention, and desire 50 to secure by Letters Patent, is—

A pole-tip comprising blades C C, held in position in slot J by rivet D, spring F and stops E E and H, and designed to be used principally on the ends of carriage and 55 wagon poles.

In testimony whereof I have signed my name to this specification in the presence of two witnesses.

JACOB THOMSEN JACOBSEN.
